SMOKE GENERATOR

Andrew F. Charwat, Los Angeles, Calif., assignor to Northrop Aircraft, Inc., Hawthorne, Calif., a corporation of California

Application February 27, 1956, Serial No. 567,786

4 Claims. (Cl. 252—359)

The present invention relates to "smoke" generators for use in examining the flow of a gaseous fluid over airfoils or other bodies positioned in a stream of said fluid, and is of the type producing a visible vapor condensation or fog as distinguished from the use of fumes or clouds of dust.

The usual use of such generators is to introduce smoke into a wind tunnel in which an airfoil is suspended, in order to examine through windows in the wall of the tunnel, the character of the air flow over the airfoil surface. Such apparatus are of increasing importance as the speed of airplanes increases and intensive study is being made of means to maintain a close adherence of the airstream to the surface of the airfoil at the high speeds.

The "smoke" should be dense and clearly visible, uniform in quality during extended runs, have good permanence in the airstream, be noncorrosive, nontoxic, and be free from deposits which clog narrow passages.

The apparatus by which the smoke is produced should be simple and reliable, automatic in action, capable of wide variation in the amount of satisfactory "smoke" produced as may be required, from a thin filament to the large quantity required to make visible an extended field of flow.

The design of a satisfactory "smoke" generator to meet the requirements mentioned provides several problems. The most suitable material has been found to be a heavy mineral oil which is heated to drive off vapor which is mixed with air to produce "smoke" by condensing the oil vapor into minute droplets of about 1 micron in diameter.

In known types of smoke generators using heavy oil vapor the oil was boiled and the vapor exhausted through a small orifice before being mixed with jets of air, but resultant condensation of the hot oil at the orifice was a source of trouble.

The rate of production of the oil vapor should be constant, requiring a constant level of the oil in the heater, a constant rate of heating the oil and avoidance of variation of conditions in the heater. In previously suggested apparatus variation in the heater is caused by injecting vapor from a jet into a stream of air, which is the only adjustable element with resultant variation of the smoke produced.

In order to meet the requirements above outlined of a satisfactory smoke generator, it is an object of the invention to provide a heating vessel in which oil is heated at a constant rate to a temperature well below the boiling point of the oil and to keep all parts of the generator below that temperature.

It is a further object of the invention to provide for removing the vapor produced by heating the oil by playing cool air on the heated surface of the oil in the heater, to condense the vapor and remove the resulting smoke through tubes of relatively large diameter, thus avoiding the use of narrow orifices through which the vapor is ejected.

2

A further object of the invention is to provide a smoke generator capable of as wide variation in the amount of smoke produced as may be required without variation in the quality of the smoke.

5 Another object of the invention is to provide a smoke generator which is flexible in adjustment, enabling the economical working of the device at good efficiency under a variety of conditions.

10 A still further object of the invention is to provide a smoke generator capable of prolonged use without the need of disassembly for cleaning, thus reducing the idle time of the device.

15 Another object of the invention is to provide a method for producing "smoke" from heated oils maintained below their boiling point.

Still further objects and features of the invention will appear from the following specification read with reference to the accompanying illustrative drawings.

20 In the drawings:

Figure 1 is a front elevation of the device of the invention;

Figure 2 is a cross section, drawn on a reduced scale, on the line 2—2 in Figure 1; and

25 Figure 3 is a schematic diagram making clear the arrangement of the various components of the device.

It should be noted that in the form illustrated the device is intended to supply smoke to a small wind tunnel in which miniature models of air foils and the like are tested.

30 Referring now to Figure 1, the numeral 10 indicates a case containing the smoke generator, this case comprises side walls 11 and 12, a base 13, top 14, and a front panel 15 carrying control valves and switches, but both front and back of the case 10 are open to facilitate access to various components of the device for reasons which will later appear.

35 The components of the device comprise a reservoir 16 for the oil used to supply the smoke, the reservoir being provided with an imperforate filler cap 17 and oil shut-off 40 valve 18 operated by handle 18a, which controls the oil supply to a constant level control means 19. The means 19 comprise a transparent, tubular, valve housing body 20, of molded Pyrex for example, formed with flanges 21 and 22. Flange 21 is clamped by end plate 23 to plate 24 on which the valve 18 is mounted, and flange 22 is clamped between plate 25 and plate 26 to which an oil delivery tube is brazed. The oil in housing 20 is maintained at a constant level by float 28 acting on a spring loaded oil inlet valve 29. The level of the oil is indicated by the dashed line 30.

45 Tube 27 delivers the oil to the heating unit generally indicated by 31. The heating unit is a cylinder with thin metal wall 32, the oil being flowed in a thin sheet through the heating unit, in the embodiment shown, by arranging 50 the cylindrical body 33 of a thermo-switch coaxially in the heater and supplying the oil to the relatively narrow space 34 between the outer surface of the body 33 and inner wall of the heater. The housing 20, heater 31 and connecting conduit form a U-shaped container so that if 55 the pressure on each end is equal, the level of the liquid in the housing will be the same as that of the liquid in the heater.

60 Heating coils 35 and 36 are wound around the outer periphery of the heater, these coils having equal values of resistance and being arranged so that they may be connected in series or parallel, as indicated in Figure 3, by switch 37. Thermo-switch 33 is of the make or break type and may be adjusted to operate at any value between 100° F. and 400° F. by setting wheel 38. The electrical 65 elements will be further referred to later.

70 A heat retaining jacket 39 is placed over the heating coils. A jet ring 40 or vapor condensing chamber is

mounted above the heater 31, and heat transfer to it from the heater is reduced by an asbestos washer (not shown) or the like and by a wire screen 42 mounted in the heater at the level 30 of the top of the oil therein. The jet ring 40 is covered by a cap 43, a second screen 44 being mounted between the top of the jet ring 40 and the cap 43. A "smoke" unrestricted outlet conduit 45 leads from the cap to a collector vessel later described.

Air under low pressure is supplied to the jet ring 40 through air inlet 46, shut-off valve 47 and pipe 48 to a valve body 50, which is manually adjusted by knurled wheel 51 to control flow to a series of jets supplied by small diameter tubes, for instance 2 as shown at 52, 53, which inject the air into the jet ring above the top of the oil. A second valve 54 is arranged to enable one jet or both jets to be supplied with air, or both jets shut off.

The remainder of the air flows through tubes 55 leading air from the outer shell of the valve and over the length of the tubes 52, 53 of the jets and exhausting into the space around the jet ring 44, thus aiding in keeping it cool.

A further path for air entering valve 50 is provided by a tube 56 leading to the collector vessel above referred to and for a purpose later described.

It is to be noted at this point that the oil heated in the heater is not boiled but that the vapor given off by the heated air is condensed to "smoke" by the cool low pressure air delivered by the jets, the construction being such as to keep the "smoke" cool.

The oil reservoir 16, oil valve housing 19 and the jet ring 40 are maintained at a common pressure by tubing 57 and a small condensate trap 58 is provided to trap any vapor condensed in the tubing.

The "smoke" flowing through outlet 45 is led to the collector and settling vessel 59 from which it is discharged through the unrestricted discharge tube 60 for use.

A regenerator or feed-back arrangement is preferably provided to improve the quality of the "smoke" especially at very low flow rates. The regenerative arrangement comprises the tube 56, the air flowing through which is controlled by the on-off valve 61, and delivers air from its nozzle end 62 into the belled end 63 of feed-back tube 64, with an injector effect which pulls some of the smoke out of the collector vessel 59. The smoke flow in tube 64 is also controlled by valve 61 and is delivered into valve 54 through jet 65 and mixes with the air passing to the jets and into the jet ring 40, the recirculated air and "smoke" being a considerable fraction of the pure air injected into the jet ring.

The regenerative action improves the quality of the "smoke" particularly at low flow rates both by maintaining circulation even at minimum rates of "smoke" production and also is believed to increase the amount of "smoke" formation by providing already formed particles of condensed vapor as nuclei for facilitating the formation of smoke particles.

The circuit by which electric current is supplied to both the thermoswitch 33 and the heating coils comprise a plug in socket (not shown) and to which a cable shown at 67 is connected. Lead 68 is connected through the make-or-break thermoswitch 33 to contact arm 69 of movable contact operating bar 70 of insulating material which may be moved to either "high" or "low" position from "off" position by the small handle 71. Lead 72 is connected between contact 73 and a connection at the mid point of heating coils 35, 36. Contact 74 is connected by lead 75 to the lower end of coil 35. Switch arm 69 may be brought into engagement with either contacts 73 or 74. A second contact 76 is connected by lead 77 to lead 75. A lead 78 is connected to the upper end of heating coil 36 and to the opposite side of the line. A second contact arm 79 is mounted on contact operating bar 70 and thus moves in unison with contact arm 69.

Arm 79 is connected to lead 78 and engages contact 76 when contact arm 69 engages contact 73 thus completing parallel circuits for coil halves 35 and 36. When arm 69 engages contact 74 a circuit is established in the coil halves 35, 36 which then are in series. The circuit arrangement enables a greater amount of heat to be supplied to the oil heater when heating the oil to start the device thus cutting down starting time and, after generation of "smoke" has been stabilized, enables the apparatus to continue in operation with lesser amount of heat. A manually operated master switch 80 enables electric current to be cut off or supplied to the apparatus, and a pilot light 81 indicates when the electric current is turned on by the switch.

15 A satisfactory oil for use in the device is a paraffin boiling at 460° F., the thermoswitch being set at about 400° F. so that boiling of the oil cannot occur. The small smoke generator described which measures about 15 inches in width, 18 inches in height and 8 inches in depth, and is therefore readily transportable, can produce a density of about 10⁹ smoke particles per cubic inch and can be adjusted to deliver from .25 cubic inch to 2 cubic inches of smoke with an input of some 250 watts at lower power.

20 The cool "smoke" produced and the relatively large diameter tubes through which it is conducted reduce condensation of the "smoke" to a minimum and such as occurs causes no clogging of the passages.

25 The use of air at a constant low pressure and the equalization of the pressures in the oil supply tank, float valve housing and oil vapor or jet chamber, with the maintenance of the oil at a substantially constant temperature which will be below boiling point of the oil, ensures steadiness of the "smoke" generation and freedom from interference from variations of pressure either within the apparatus or due to outside causes.

30 The flexibility of output without variation in quality of smoke or instability in rate of smoke generation is believed to be much better than that obtained by previously proposed devices.

35 While in order to comply with the statute, the invention has been described in language more or less specific as to structural features, it is to be understood that the invention is not limited to the specific features shown, but that the means and construction herein disclosed comprise a preferred form of putting the invention into effect, and the invention is therefore claimed in any of its forms or modifications within the legitimate and valid scope of the appended claims.

40 What is claimed is:

1. In vapor or "smoke" generating apparatus, the combination comprising: a liquid heating chamber; means adapted to supply liquid and heat to said heating chamber; a thermostat in said heating chamber adapted to maintain the temperature of liquid in the latter below the boiling temperature of said liquid; a vapor receiving chamber contiguous with and arranged above said heating chamber; unrestricted conduit means adapted to convey vapor from said vapor receiving chamber; a first metal screen positioned at the top of said heating chamber to provide a perforated partition between the latter and said vapor receiving chamber; tubes adapted to deliver a cool gaseous medium into said vapor receiving chamber in a direction to impinge on said first screen; first conduit means adapted to deliver a gaseous medium to said apparatus; second conduit means communicating with said first conduit means and staid tubes; and valve means adapted to direct a portion of said gaseous medium flowing through said second conduit means to said tubes and the remainder against the outside walls of said vapor collecting chamber.

2. Apparatus as set forth in claim 1 and in addition including a second wire screen arranged in said vapor collecting chamber between the area of introduction of cool gaseous medium thereinto and the unrestricted

conduit means leading condensed vapor or "smoke" out of the apparatus.

3. Visible vapor or "steam" generating apparatus comprising: a liquid heating unit; means supplying liquid and heat to said unit; said unit including a chamber receiving vapor from said unit; a thermostat mounted in said unit and adapted to maintain the heat of said liquid below the boiling point thereof; means maintaining said vapor receiving chamber at a relatively low temperature; means injecting a gaseous medium under pressure and at a lower temperature than said vapor into said vapor receiving chamber; unrestricted conduit means leading the vapor condensed in said vapor receiving chamber out of the unit for use; a settling vessel into which the condensed vapor or smoke from the vapor receiving chamber is led; unrestricted conduit means leading the condensed vapors or smoke from said settling chamber out of the apparatus for use; and means for recycling a portion of the condensed vapor or "smoke" from the settling chamber into the gaseous medium introduced into the vapor receiving chamber.

4. Apparatus as set forth in claim 3 in which said means for recycling a portion of the condensed vapors or smoke comprise: an injector positioned in said settling chamber; a conduit leading gaseous medium under pressure to said injector; conduit means leading from said injector to lead "smoke" injected therein to the conduit leading gaseous medium into said vapor receiving chamber; and valve means controlling the conduits for recycling a portion of the "smoke."
